UNITED STATES PATENT OFFICE

HOWARD D. RANDALL, OF CINCINNATI, OHIO, ASSIGNOR TO THE RANDALL COMPANY,
A CORPORATION OF OHIO

RUNWAY FOR SLIDING PANES

Application filed July 15, 1930. Serial No. 468,064.

This invention relates to improvements in a runway for a sliding window pane or panel.

An object of the invention is to provide a runway structure for panels, such as window panes or the like, which will close itself to the entry of foreign substances, such as water and dirt, during such times as the runway is unoccupied by said pane or panel.

Another object is to provide a runway structure which may be very inexpensively manufactured.

Another object is to provide a runway structure of the above character which is durable and pleasing in appearance.

15 These and other objects are attained by the means herein described and disclosed in the accompanying drawing, in which:

Fig. 1 is a cross-sectional isometric view showing a support with the runway structure 20 applied thereto.

Fig. 2 is an elevational view showing the support and runway of Fig. 1 associated with a pane of glass or the like.

Fig. 3 is a cross-sectional view of a modified 25 form of runway structure.

The runway structure of the present invention comprises a longitudinal body 4 having a base portion 5 and integral sides 6 extending therefrom in substantial parallelism and 30 in a common direction. It is of importance that the body 4 be constructed of a very springy or resilient substance, such as sponge rubber, a composition thereof, or other material having comparatively great compressibility, for the sides 6 thereof are thereby caused to normally contact, or substantially contact, one another for closing the runway, or that portion thereof, which is unoccupied by a pane or panel as indicated in Fig. 2.

40 The inner faces 7 of the sides 6 normally converge from the base portion toward the mouth 8, and said faces preferably are covered by felt or other suitable material 9 that will permit of free sliding movement of the pane in the runway.

45 As indicated in the drawing, the felt covering consists of a ribbon-like strip which lies upon the base portion and the inner faces of the sides, the free edges 10 thereof being drawn over the inwardly extending lobes 11 of the sides and

secured to the body by means of suitable clinch members 12. The clinch members may be provided with a bead-like clamp portion 13 and an anchor portion 14, the portion 13 being adapted to contact and force the felt 55 edges into the material of the body, and the portion 14 being adapted to enter and embed itself in the outer face of the side 6 for holding the felt edge in position. Holding means other than the metallic member 12 obviously 60 could be employed for holding the felt and for providing a neat and finished edge. The member 15, having the channel 16 formed therein, may be any suitable type of support, such as a vehicle body member or the like.

Securing means such as nails or screws 16 may provide a means of holding the runway structure in position within the channel 160. Cementitious substances also are commonly used for the purpose. The felt or pane contacting member may be cemented upon the body, if desired, in which case the longitudinal edge 10 thereof could be fastened adjacent the bead instead of being held thereby.

70 From the foregoing it will be readily apparent that, due to the compressible character of the body portion of the runway structure, and the provision of the longitudinal lobes or inwardly extending ribs 11, a runway structure is provided which may 75 completely close itself when occupied by a pane or panel 17, as indicated in the upper portion of Fig. 2. Whether or not the runway is to close itself entirely is a matter of choice, for it may be desirable to provide 80 for a very narrow opening between the sides in order to facilitate drying out the interior of the runway in the event that moisture be permitted to enter. The runway may be said to substantially close itself.

85 In Fig. 3 is disclosed a modified form of runway structure wherein 20 indicates the body portion which may be of sponge rubber or similar material, the numerals 21 indicating longitudinal individual strips of felt or the like for contacting a pane of glass. In the modified structure, the clinch members are indicated at 22, and they are embedded in the body portion in the manner above described. The sponge rubber body portion 100

insures easy sliding of a pane in the runway.

It is to be understood that various modifications and changes in structural details may be made in the device within the scope of the 5 appended claim, without departing from the spirit of the invention.

What is claimed is:

In a runway structure, the combination of a body portion comprising a base portion and 10 sides of compressible material, the sides each having an outer and an inner face, portions of the inner faces being disposed normally in substantially contacting relationship, a covering extending from the outer face of 15 one side to the outer face of the other side for covering the inner faces of the sides and base portion, and a beaded member having an anchor portion embedded in one of the outer faces and a clinching portion holding the 20 covering in position.

In testimony whereof, I have hereunto subscribed my name this 12th day of July, 1930.

HOWARD D. RANDALL.
